UNITED STATES PATENT OFFICE

2,048,261

SELECTOR FOR CALCULATING MACHINES

Ernst Valfrid Gustafsson, Stockholm, and Gustaf Hilarius Hellgren, Karberg, Vallentuna, Sweden

Original application December 21, 1928, Serial No. 327,587. Divided and this application March 14, 1932, Serial No. 598,647. In Sweden December 23, 1927

8 Claims. (Cl. 235—60)

This application is a division of our copending application, Serial No. 327,587, filed December 21, 1928, now Patent No. 1,930,475, granted Oct. 17, 1933.

5 The present invention relates to a selector for calculating machines. Selectors of this kind are generally provided with stopping members, sometimes also called stop pins or stop tongues, which are set by means of the numeral keys of the calculating machine and themselves serve as stops for the levers or mechanisms which operate the calculating members proper. In order to render visible the figures set up in the selector, calculating machines hitherto known are often provided 10 with a special counter which is operated by the stop members through the intermediary of appropriate lever systems or the like.

According to the present invention the stop members, pins, tongues or the like are provided 20 at their ends with the same figure as corresponds with the numeral key pressed down, the arrangement being such that the stop members with their figures will become visible, when the stop members or the like are caused to project somewhat 25 from the selector by pressing down the corresponding numeral keys.

One preferred form of embodiment of the invention will be more fully described in the following with reference to the accompanying drawings which refer to a calculating machine having 30 ten keys only.

Fig. 1 shows perspectively a calculating machine having an opening through which the stop members with their figures thereon become visible. Fig. 2 is an elevational front view of the calculating machine with the front part of the casing broken away. Fig. 3 shows a lateral view of the selector, partly in section. Fig. 4 shows a longitudinal section through the selector. Figs. 5 and 40 6 show a stop member or tongue in two different views.

The calculating machine is enclosed in a casing 1 which is provided with windows 2 and 3 for the result register and the quotient register or handle 45 stroke counter, respectively. The casing is further provided with a special opening 4, through which the stop members 5 with the figures at their free end become visible. The stop members shown in Fig. 1 represent the figure 964. The 50 main shaft 6 of the calculating machine projects on the right hand side of the casing and is provided, in known manner, with a handle 7 which is adapted to be rocked to and fro for carrying out a calculating operation. On a front board of the casing are to be found the conventional nu-

merals keys representing the numerals 0 to 9 and several other keys for setting the calculating machine for addition, subtraction, multiplication and division operations.

The selector (Figs. 2, 3 and 4) consists of a 5 frame which is constituted by an upper arcuated plate 8, a lower arcuated plate 9 and two end plates 10 and 11. The frame supports two pairs of gliding rollers 12, 13 and 14, 15, the upper pair 12, 13 of which is adapted to roll on an upper 10 guiding bar 16, while the lower pair 14, 15 is adapted to roll on a lower guiding bar 17. The arcuated plates 8 and 9 are provided with rows of slots, the slots in the lower plate 9 registering with the slots in the upper plate 8. Each row 15 comprises, seen from the key board, ten slots behind each other (Fig. 3), and the number of rows of slots depends on the desired capacity of the calculating machine. In the present case (Figs. 2 and 4), nine such rows of slots are arranged. In each of these pairs of slots formed in the said manner in the plates 8 and 9, a stop member 5 is inserted and adapted to slide therein. A stop member or tongue provided with the figure 1 is shown on a larger scale in Figs. 5 and 6. 25 Each stop member or tongue has a lateral shoulder 18, with which it normally rests on the lower plate 9 in such a manner that the upper edge of the stop member lies flush with the outer surface of the upper plate 8. The stop member or tongue 30 is further provided, for instance by way of stamping, with a lateral projection 20 and an opening 21 formed by such stamping. In this connection it is to be mentioned that in Fig. 2 the tongues having the numeral 1 are visible, while the other 35 tongues having the figures 2 to 9 are to be found behind the first named tongues. The section shown in Fig. 4 is taken between the tongues having the figures 4 and the tongues having the figures 5. The tongues extend through the selector 40 in radial direction with respect to a point of rotation 22 (Fig. 3), about which a member 23 for setting the calculating mechanism proper (not shown) may be rocked. This member 23 is rocked to and fro, when operating the handle 7, by means 45 of appropriate devices which do not form a part of the present invention and therefore are not shown. The member 23 has a finger-like extension 24 which is adapted to move through the openings 21 in all those tongues 5, which have not 50 been operated by the numeral keys. When, however, a tongue is pressed out by a numeral key in radial direction, for instance the first tongue reckoned from the left in Fig. 3 and indicated by dotted lines, or the first tongue to the left shown 55

in Fig. 4, the finger-like extension 24 will abut with its front end the full material 25 of the tongue below the opening 21, so that the tongue serves as stop means for the calculating member 5 23 and in this manner causes the proper setting of the calculating member in correspondence to the numeral key pressed down.

The tongues are pressed out by means of the following mechanism. At an intermediate wall 10 28 in the interior of the calculating machine a bracket 27 is fixed. This bracket has an arcuated ride 27a supporting ten levers 28, one for each tongue in the same row. Each lever has a hammer-like projection 31 which is arranged 15 just outside of the lower end of each tongue. The other free end 31a of the lever 28 supports pivotally a rod 29 which is pivoted to the corresponding numeral key. For the sake of clearness one rod only has been shown, and this is supposed to 20 be connected with the numeral key 30 for the figure "1". The other rods are shown only partly. When a numeral key, for instance the key 30, is pressed down, the lever 28 is swung, with the ridge 27a as pivot, in clockwise direction, where- 25 by the hammer 31 presses the corresponding tongue upwards. At the same time the selector is caused in a manner known per se to move a step to the left. As illustrated in Fig. 2, the key 30 has been pressed down three times, so that the 30 figure 111 will appear. When now the calculating machine is operated by means of the handle 7, this figure 111 will be transferred to the result register 32 in a manner known per se and not forming a part of the present invention. 35

When the selector is moved stepwise to the left, the tongue which has been pressed out, glides with its lateral extension 20 upon a rod 33 which is fixed to the left side wall 34 of the calculating machine. The left side plate 10 of 40 the selector is provided with holes 35 which serve as guiding means for the rod 33, when the selector moves to the left (see Figs. 3 and 4). For each series of tongues a rod 33 is provided, so that ten such rods exist. 45

When the selector upon the completion of a calculating operation is again moved to its initial position (to the right in Figs. 2 and 4), the tongues pressed out glide down from the rods 33 and fall by their own weight into their initial 50 position, that is to say they rest with their notches 19 on the upper side of the lower plate 8 of the selector. As will be seen from Fig. 4, eight such tongues have already attained the initial position, while the last or ninth tongue 55 still rests on its rod 33.

If for any reason the tongue should not automatically return to its initial position, which may easily occur for the last tongue at the right hand side of Figure 3, inasmuch as its return movement must be effected approximately in horizontal direction, such tongues are compulsorily pressed back during the return of the selector frame to its normal position. 60

A plate 36 of the same arcuated shape as the upper plate 8 of the selector is pivoted to two brackets 38 and 39 fixed to the right hand side wall 37 of the machine, in such a manner that the plate normally rests closely on the upper plate 8 of the selector. At its free (left hand side) end the plate is bent upwards in order to form an inclined surface 40. At the return movement of the selector the tongues pressed out engage this inclined surface, and this engagement is generally sufficient to press the 75 tongues back to the initial position. It may,

however, happen that this pressure not always is sufficient, because the plate 36 acts on the tongues only by its own weight. In order to compulsorily return the tongues, the plate 36 is provided near its pivoted end with an extension 41 projecting downwardly. When a tongue is not moved back by the plate, it will lift the plate by engaging the inclined surface 40 thereof. At the extreme end of its return stroke the selector engages with its right hand side end wall 11 said extension 41 10 on the plate 36 which by this means will be compulsorily pressed against the upper surface of the selector plate 8, whereby tongues which still may be projecting beyond the upper plate 8 are pressed back to the initial position. It will be 15 understood that there is a slight rebound movement of the selector frame, from its extreme end position towards the right, before the retaining pawl of the step-by-step mechanism engages with the first tooth of the rack. This excess 20 movement towards the right, which is customary in the similar carriage mechanisms of typewriters, permits the selector to force the return of all of the tongues 8 to normal position without, however, preventing the subsequent displacement 25 of the first tongue 8 into operative position by a numeral key. For a more detailed description of the mechanism for effecting the step-by-step and the return movement of the selector carriage, reference is made to the aforesaid Patent No. 30 1,930,475.

On account of the fact that the figures provided on the tongues are made visible in a simple manner immediately upon the tongues being operated by actuating a numeral key, the important 35 advantage is gained that faults which may depend on some faultiness in counters which have been utilized in calculating machines hitherto known, are entirely avoided, and on the other hand faults which are caused by inadvertently 40 operating a wrong key may be immediately observed and rectified, before the numeral in question is introduced into the calculating members proper of the machine.

What we claim is:—

1. In a calculating machine, the combination with a machine casing provided with an opening, and numeral keys, of a selector within said casing and progressively movable into view through said opening upon operation of said keys; said selector comprising a frame, control members movably supported in said frame, said control members each being provided with a numeral at an end portion thereof and the said end portions being normally concealed within said selector, key-actuated means for moving said control members to project the numeral-bearing portion thereof into view outside said selector, and means for supporting the key-projected control members in projected position upon movement of the selector frame. 55

2. In a calculating machine, the combination with a machine casing provided with an opening, and numeral keys, of a selector within said casing and progressively movable into view through said opening upon operation of said keys; said selector comprising a frame, control members movably supported in said frame, said control members each being provided with a numeral at an end portion thereof and the said end portions being normally concealed within said selector, key-actuated means for moving said control members to project the numeral-bearing portion thereof into view outside said selector, and means stationary relative to said 70 selector. 75

selector frame for supporting the key-projected control members in projected position upon movement of the selector frame.

3. In a calculating machine, the combination with a machine casing provided with an opening, and numeral keys, of a selector within said casing adjacent said opening; said selector comprising a slotted frame, control members movably supported on said frame and each provided with a number at the end thereof adjacent the opening in the casing, said control members being adapted to enter slots in said frame upon relative longitudinal movement of said control members and said frame, key-actuated means for selectively projecting towards said casing opening those control members corresponding to a desired numerical value, means for retaining the projected control members in projected position, and means operative upon the actuation of a key to move said selector frame into exposed position through the opening of said casing, said selector frame including means for concealing the numeral-indicating ends of the non-projected control members from view through said casing opening, whereby the numeral-indicating ends of only the projected control members are exposed for view above said concealing means.

4. In a calculating machine, the combination with a machine casing provided with an opening, and numeral keys, of a selector within said casing adjacent said opening; said selector comprising a frame, control members movably mounted in said frame, said control members each having a value-indicating end portion normally located within said selector frame, key-actuated means for moving said control members to project the said end portions thereof to the exterior of the selector frame, thereby to set up a numerical value for controlling the operation of the calculating machine, means actuated upon the operation of said number keys to move said selector frame, and means stationary relative to said selector for supporting the key-projected control members in projected position upon movement of the selector frame, whereby the numerical value set upon said selector is displayed at said casing opening.

5. In a calculating machine, a casing provided with an opening, numeral keys, and a selector within said casing and movable upon operation of said keys; said selector comprising an arcuate frame, control members mounted for radial movement in said frame and each having a

value-indicating number at its outer end, key-actuated means for radially moving the desired control members to project the outer ends thereof into view outside said selector, and means stationary relative to said frame for supporting the projected control members with the value-indicating ends thereof visible through said casing opening.

6. In a calculating machine, numeral keys, a selector mounted in said machine and including a frame movable upon operation of said keys, control members movably mounted in said frame, means for actuating said control members upon operation of said keys, means stationary relative to said frame for supporting the actuated control members upon movement of said frame, and means actuated by said frame during its return to initial position for positively returning the actuated control members to their original positions.

7. In a calculating machine, numeral keys, a selector mounted in said machine and including a frame movable upon operation of said keys, control members movably mounted in said frame, key-operated means for projecting the end portions of selected control members to the exterior of the frame, means stationary relative to the frame for supporting the selected control members in projected position upon movement of the frame, and a pivotally supported member for returning the projected control members to initial position, said member being actuated by the frame during the return thereof to its initial position.

8. In a calculating machine, numeral keys, a selector mounted in said machine and including a frame movable upon operation of said keys, control members movably mounted in said frame, key-operated means for projecting the end portions of selected control members to the exterior of the frame, means stationary relative to the frame for supporting the selected control members in projected position upon movement of the frame, and a pivotally supported member for returning the projected control members to initial position during the return of the frame to its initial position, said pivotally supported member having an extension adapted to project into the path of movement of the frame as it approaches its original position.
